SUPERHEATER

André Huet, Paris, France, assignor to The
Superheater Company, New York, N. Y.

Application November 15, 1933, Serial No. 698,094
In France April 5, 1933

6 Claims. (Cl. 122—476)

The present invention has for its object an improvement in steam superheaters either separately fired or combined with a boiler.

It happens at times when the water level is too high or from some other reason, that water is entrained from the boiler to the superheater. This causes several difficulties, all of which are well known at present and will not be mentioned in detail.

10 The improvement forming the object of the present invention has been made with a view to avoiding said difficulties and makes it possible to separate from the saturated steam at its entrance to the superheater any water which it may 15 contain.

The invention is characterized by the fact that the superheater header or collector for the saturated steam, which is preferably inclined, is arranged in such a fashion that the steam does not 20 pass directly into the tubular superheater elements but experiences changes in direction such that the water will be separated from the steam and flows downward along the lowest part of the header without being able to enter the elements, 25 to be subsequently eliminated by suitable means which may be automatic or otherwise.

The description which follows, which is given by way of example and which is to be read in connection with the accompanying drawing, will 30 make it possible to understand in what way the invention can be carried out. In the drawing,

Fig. 1 is a partial vertical section of a water tube boiler provided with a superheater in accordance with the invention.

35 Fig. 2 is a partial section on line 2—2 of Fig. 1. Fig. 3 is a detail viewed from above of the header 6 on the section line 3—3 of Fig. 2.

The boiler illustrated comprises a lower water drum 1 connected to the steam and water drum 2 40 by means of tubes of which those which are nearest to the source of heat serve as risers for the water and steam while those further removed serve as return tubes.

Between the last bundle 3 of riser tubes and the 45 first bundle 4 of return tubes there is installed a superheater composed of tubular units 5 connected at their ends to a saturated steam header 6 and a superheated steam header 7. The saturated steam is taken from the drum 2 of the boiler 50 to the header 6 by means of the pipe 8.

The header 6 is preferably somewhat inclined from the vertical. As will be evident from an inspection of Fig. 2, the openings 9 of the header 6 to which the ends of the units 5 are connected 55 are not arranged along the lower side of the

header 6, but preferably about 90 degrees from this lower line. It is evident the water in the steam in header 6 will mostly drop to the bottom and so will be prevented from entering the elements 5 through openings 9.

Baffles 11 are arranged in header 6, due to the presence of which the steam arriving through the pipe 8 is hindered from flowing directly into the elements 5 but must most of it strike these baffles and will by them be deflected so that the water 10 contained in the steam is separated from it. As illustrated, the baffles 11 are plates extending longitudinally of header 6 and arranged to project substantially radially of such header. There are 15 two baffles 11 shown, which are fixed to the inner face of header 6 at their outer edges one on each side of the zone in which the superheater units are attached to the header, but their radial extent is limited so that they do not meet at their inner edges and there is a space 11a between such edges 20 for steam to pass to units 5. In order, however, that water may not be carried directly into the space between baffles 11, I prefer to place a cover 11b over them at the ends first encountered by the steam. The water thus separated will necessarily flow along the lower side of the header and 25 accumulate in its lowest part.

In order that this water may be collected without its level ever standing as high as the openings to the lowest units 5, the header 6 may be 30 extended downwardly or may be connected by means of a connector 12 to a water chamber 13 as is shown in the drawing, such chamber being provided with a water level indicator 14 and a blow-off connection 15. This pipe may be either 35 controlled by a blow-off cock 16 which can be manually operated whenever this is thought necessary from the indication of the water level indicator 14 or by an automatic blow-off.

Modifications in the detail may be introduced 40 in the invention without necessarily avoiding its spirit. For example, the separation of the water and steam may be made by means of the shape and arrangement of the header 6 itself without 45 use of any baffles.

I claim:

1. In a superheater; a header; superheater units connected into the side wall of said header in a zone extending longitudinally thereof and located between the uppermost and lowermost 50 portions of said side wall; a supply pipe connecting into said header at one end thereof for admitting saturated steam to said header at a point spaced longitudinally thereof from the inlets of said units; and baffling means extending along 55

the lower side of said zone for diverting water carried by the steam away from the inlets of said units.

2. In a superheater; a header; superheater units connected into the side wall of said header in a zone extending longitudinally thereof and located between the uppermost and lowermost portions of said side wall; a supply pipe connecting into said header at one end thereof for admitting saturated steam to said header at a point spaced longitudinally thereof from the inlets of said units; and baffling means extending along either side of said zone for diverting water carried by the steam away from the inlets of said units.

3. In a superheater; a header; superheater units connected into the side wall of said header in a zone extending longitudinally thereof and located between the uppermost and lowermost portions of said side wall; a supply pipe connecting into said header at one end thereof for admitting saturated steam to said header at a point spaced longitudinally thereof from the inlets of said units; baffling means extending along said zone at either side thereof for diverting water carried by the steam away from the inlets of said units; and means associated with said baffling means adjacent the end thereof nearest said pipe connection for preventing water carried by steam flowing along said header towards said inlets being forced into said zone between the end portions of said baffling means.

4. In a superheater; a header; superheater units connected into the side wall of said header in a zone extending longitudinally thereof and located between the uppermost and lowermost portions of said side wall; a supply pipe connecting into said header at one end thereof for admitting saturated steam to said header at a point spaced longitudinally thereof from the inlets of said units; a pair of baffle members extending along said header and projecting inwardly from the interior wall thereof at either side of said zone with their inner edges spaced to provide a

slot therebetween for admitting steam to said zone and thence to the inlets of said units; and means at the ends of said members near said supply pipe for closing the space between the end edges of said members to prevent water entering 5 between the spaced end edges of said members.

5. In a superheater; a header; superheater units connected into the side wall of said header in a zone extending longitudinally thereof and located between the uppermost and lowermost 10 portions of said side wall; a supply pipe connecting into said header at one end thereof for admitting saturated steam to said header at a point spaced longitudinally thereof from the inlets of said units; a pair of baffle members extending 15 along said header and projecting inwardly from the interior wall thereof at either side of said zone with their inner edges spaced to provide a slot therebetween for admitting steam to said zone and thence to the inlets of said units; and 20 means at the ends of said members near said supply pipe for closing the space between the end edges of said members and extending partially along said inner edges to close a part of said slot to prevent water entering said zone between the 25 end portions of said members.

6. In a superheater; an inclined header; a saturated steam supply pipe connected into said header at the upper end thereof; superheater units connected into the side wall of said header 30 in a zone extending longitudinally thereof below said supply pipe and located between the upper and lower, inclined surface portions of said side wall; baffling means extending along said header at either side of said zone, said baffling means 35 acting to divert water carried by steam admitted to the header away from the inlets of said units and the inclination of said header causing the water to flow along the lower inclined surface thereof to the lower end of said header; and 40 means at the lower end of said header for draining the water from the header.

ANDRÉ HUET.
